UNITED STATES PATENT OFFICE.

WILLIAM C. BANKS, OF COMO DEPOT, MISSISSIPPI, ASSIGNOR TO REBECCA BANKS, OF SAME PLACE.

IMPROVEMENT IN COTTON-BALE TIES.

Specification forming part of Letters Patent No. 152,823, dated July 7, 1874; application filed December 24, 1873.

To all whom it may concern:

Be it known that I, WILLIAM C. BANKS, of Como Depot, in the county of Panola and State of Mississippi, have invented a new and Improved Cotton-Bale Tie; and I do hereby declare that the following is a full, clear, and exact description of the same, reference being had to the accompanying drawing forming a part of this specification, in which—

Figure 1 is a perspective view of a portion of the bale-tie.

The invention relates to, and consists in, novel means for tying with facility, and without possibility of slip, the two ends of a bale-tie, as hereinafter more fully described.

A represents a band of thin sheet metal, and B a buckle having apertures b b, intermediate tongue b¹, and the side opening b². The tongue b¹ projects into the middle of the side opening b², and is bent down at the end below the plane of the side pieces b³ b³. In one of the apertures b of the buckle is secured, by bending, or in any suitable manner, end a¹ of band, while at a proper distance from the other end, a², is formed the crimp a.

The band is placed around the bale and drawn tightly, when the crimp a is made at the proper distance from end a², and slid laterally over the tongue b¹. This causes the end a² to project under end a¹ while the band is in both apertures of buckle, and over the tongue. This produces an excellent tie, that can be applied with great rapidity to bale after bale, and allows the band to be drawn to any degree of tightness, and yet to never jostle or work off.

Having thus described my invention, what I claim as new, and desire to secure by Letters Patent, is—

The combination of band A and buckle B, the former crimped near one end, and the latter having the tongue b¹ bent below the plane of side pieces b³ b³, as and for the purpose described.

WM. C. BANKS.
